UNITED STATES PATENT OFFICE.

EMMETT W. STULL, OF MILWAUKEE, WISCONSIN, ASSIGNOR TO ALLIS-CHALMERS COMPANY, A CORPORATION OF NEW JERSEY.

CONTROLLER.

1,018,019.

Specification of Letters Patent.

Patented Feb. 20, 1912.

Application filed July 20, 1910. Serial No. 572,892.

To all whom it may concern:

Be it known that I, EMMETT W. STULL, a citizen of the United States, residing at Milwaukee, in the county of Milwaukee and 5 State of Wisconsin, have invented certain new and useful Improvements in Controllers, of which the following is a full, clear, and exact specification.

My invention relates to electric controllers.

It is the object of my invention to provide an improved form of controller, particularly in the construction of the controller drum. This is accomplished by molding the drum body, which is preferably mounted on a shaft of magnetic material, of some plastic insulating material, and molding in this insulating material certain metal parts. There may be two sets of 15 these metal parts, though in some cases either set may be omitted. The plugs of one set are for furnishing means for fastening the contact segments to the drum body; and those of the other are located near the 20 ends of certain contact segments for the purpose of diminishing the reluctance of the magnetic path between the controller shaft and certain other parts to assist the 25 action of a magnetic blowout.

30 The various novel features of my invention will be apparent from the description and drawings, and will be particularly pointed out in the claims.

Figure 1 is a horizontal section of a controller embodying my invention; and Fig. 2 is a partial front elevation of such controller, with the cover removed and some parts in section.

The controller frame 10 has one or more 40 inwardly extending projections 11 in which is journaled the controller shaft 12. On this controller shaft is a molded drum body 13, formed in a suitable mold of some plastic insulating material. The drum body 13 45 is fundamentally cylindrical in shape, but has certain projections 14 in which are located iron parts 15. These parts 15 are preferably non-integral with the shaft 12 and are in the form of plugs flared at their inner 50 ends to obtain a firm anchorage in the insulating material forming the drum body. They extend from points close to the shaft 12 to points at or near the outer surfaces of the 55 projections 14. The outer ends of the plugs 15 are shown with internal screw threads,

which may be provided for the purpose of enabling such plugs to be held firmly in the mold. Other plugs 16, likewise flared at their inner ends to provide an anchorage, are also embedded in the insulating material forming the drum body 13. These plugs 16 are screw-threaded internally for two purposes; to enable them to be held firmly in place during the molding operation, and to provide threads for engagement with the screws 17 which hold in place plates 18 on which the contact segments 19 of the controller are mounted. The segments 19 coöperate with stationary contact fingers 20, preferably located between insulating septa 21. An iron bar 22 is located just beyond the ends of the contact fingers 20 in the same plane with such ends and the shaft 12, and this bar 22 is mounted on suitable iron arms 23 fastened 60 to one or more bosses 24 on the frame 10. The bar 22 and the shaft 12 thus form opposite poles of a magnetic circuit energized by a blowout coil or coils 25 mounted on the projection or projections 11. This magnetic 65 circuit includes the bar 22, arms 23, bosses 24, frame 10, projections 11, and shaft 12, and the ends of the fingers 20 are located in the air gap between the bar 22 and the shaft 12. Any breaking of circuits between 70 the contact segments 19 and the contact fingers 20 thus takes place in this air gap, and thus is disrupted magnetically. It is 75 in order to lessen the length of this air gap and thus to increase the efficiency of 80 the blowout that the plugs 15 are provided, these plugs being located near those ends of any or all of the contact segments 19 at which breaking of the circuit takes place.

Many modifications may be made in the 95 precise arrangement shown and described, and all such which do not depart from the spirit and scope of my invention I aim to cover in the following claims.

What I claim as new is:

1. In a controller, a shaft of magnetic material, a drum molded of plastic insulating material on said shaft, a contact segment mounted on said drum, and an iron plug molded in such drum adjacent to an 100 end of such segment.

2. In a controller, a shaft of magnetic material, a molded insulating drum mounted on said shaft, contact segments mounted on said drum, contact fingers co- 105

operating with said contact segments, means for producing a magnetic field extending from the shaft across the space occupied by the ends of said contact fingers, and parts of magnetic material embedded in said drum adjacent to ends of said contact segments.

3. In a controller, a shaft of magnetic material, a molded insulating drum 10 mounted thereon, a contact segment mounted on said drum, a part of magnetic material embedded in the drum adjacent to an end of said contact segment, a contact finger operating with said segment, a plate of 15 magnetic material on the other side of said contact finger from said drum, and means

for creating a difference of magnetic potential between said plate and said shaft.

4. In a controller, a shaft of magnetic material, an insulating drum mounted 20 thereon, a contact segment mounted on said drum, and a plug of magnetic material flared at its inner end and embedded in said drum.

Milwaukee, Wis., July 1, 1910. 25
In testimony whereof I affix my signature, in the presence of two witnesses.

EMMETT W. STULL.
